FURNACE HOT-WATER HEATER

Frank J. Gorman, Reno, Nev.

Application January 15, 1944, Serial No. 520,419

21 Claims. (Cl. 237—2)

1

My invention relates to improvements in a furnace hot water heater, and it consists of the combinations, constructions and arrangements hereinafter described and claimed.

This application is a continuation-in-part of my abandoned application on a furnace hot water heater, filed August 3, 1938, Serial Number 222,798.

An object of my invention is to provide a furnace hot water heater in which the same hot air furnace that is used for warming the rooms of the house is also used for heating water for a hot water tank. In this way, an installation of a hot air furnace and a separate hot water heating plant is avoided with a resulting saving in cost.

The type of furnace used is one which has a hot air duct leading to various rooms and a cold air return duct leading from the rooms back to the furnace. In this way, a closed circuit of heated air from the furnace to the rooms and from the rooms back to the furnace is maintained. I provide a separate hot air or heater duct communicating with the furnace hot air duct and with the cold air return duct. In the heater duct, I dispose a hot water heater and connect this with the hot water tank. Dampers are provided in the two closed circuits and are automatically controlled by a room thermostat and by an aquastat for causing the hot air to flow to the rooms when the room thermostat calls for heat or to pass through the heater duct when the aquastat calls for heat. In winter time, hot air is caused to flow through both the hot air duct and the heater duct. Very little extra heat is necessary for heating the water in the hot water tank because the heated air follows a closed circuit path from the furnace, through the heater duct and back to the furnace.

A modified form of the invention is also disclosed wherein the casing has a partition dividing it into two chambers, one for the furnace and the other for the blower and the cold air return. I mount a by-pass damper in the partition and place the hot water heater in the furnace chamber and adjacent to the damper so that some of the furnace hot air will pass the water heater when the rooms are being heated and all of the hot air will pass the water heater when the room dampers are closed and the by-pass damper is open. This does away with the need of a second casing for the water heater.

Other objects and advantages will appear in the following specification, and the novel features

2

of the device will be particularly pointed out in the appended claims.

My invention is illustrated in the accompanying drawing forming a part of this application, in which

Figure 1 is a schematic showing of the entire device;

Figure 2 shows the hot water radiator on an enlarged scale;

Figure 3 is a wiring diagram for the device shown in Figure 1;

Figure 4 is a schematic showing of a modified form of the device;

Figure 5 is a wiring diagram for the device shown in Figure 4;

Figure 6 is a schematic showing of another modified form of the invention;

Figure 7 is a schematic showing of still another modified form of the invention; and

Figure 8 is an alternative wiring diagram for the devices shown in Figures 1, 4 and 6.

In carrying out my invention, I provide a hot air furnace indicated generally at 1 and this furnace may be of any standard type desired. A hot air duct 2 leads from the furnace to the various rooms and a cold air return duct 3 conveys the air from the rooms back to the furnace for reheating. A damper 4 is placed in the hot air duct and is actuated by a thermostatically operated control motor indicated generally at 5. Any type of operative connection between the motor 5 and the damper 4 may be used and I have shown an arm 6 actuated by the thermostatically operated control motor 5 and connected to a damper arm 7 by means of a link 8. In Figure 1, I show the damper 4 held in open position by the damper arm 7.

A room thermostat 9 is electrically connected to the thermostatically operated control motor 5 in the customary manner and I have shown an electric conduit 10 extending from the thermostat 9 to the motor 5. The motor circuit is closed and opened by the room thermostat 9 in a manner hereinafter described. The room thermostat 9 may also be connected to an electrically controlled gas valve indicated diagrammatically at 11. An electric conduit 12 leads from the room thermostat 9 to the valve 11. The valve controls the flow of gas through a gas pipe 13 to a burner 14 and a pilot light 15 ignites the gas. It is obvious that an oil burner may be used in place of a gas burner as shown in my modified form, if desired, and that a forced draft through the furnace may be effected by a fan or blower 47.

The parts thus far described, are of standard construction and form no part of my invention except insofar as they cooperate with the parts now to be described. A hot air or heater duct 16 communicates with the hot air duct 2 at a point below the damper 4 and also communicates with the cold air duct 3 at a point adjacent to the furnace. A damper 17 is disposed in the inlet end of the heater duct 16 and is operatively connected to the damper 4 so that the damper 17 will be partially opened when the damper 4 is entirely opened and a closing of the damper 4 will entirely open the damper 17. Any type of connection between the two dampers for effecting this operation will suffice and in the drawing I have shown a link 18 connected to a damper arm 19 which in turn is actuated by the damper 4. The link 18 operates a bell-crank lever 20 and the lever is connected by a link 21 to a damper arm 22 that is connected to the damper 17.

I dispose a hot water heater 23 in the heater duct 16 and this heater is shown on a larger scale in Figure 2. The heater has an upper header 24 and a lower header 25 connected together by pipes 26. The heater is connected to a hot water tank 27, see Figure 1, by means of a cold water pipe 28 that leads to the header 25 and a return hot water pipe 29 that leads to the header 24. The tank 27 is provided with a cold water inlet pipe 30 and a hot water outlet pipe 31 in the usual manner. Any type of heat transferring means may be placed in the duct 16. The drawing shows a tube and fin type of hot water heater although a honeycomb type may be used.

I mount an aquastat 32 in the hot water tank and this controls the electric gas valve 11 through the medium of an electric conduit 33 that connects the aquastat with the valve. When the water temperature in the tank 27 drops below a predetermined point, the aquastat will cause the electric valve 11 to open in a manner presently to be described and the pilot light 15 will ignite the gas issuing from the burner 14. The heated air flowing from the furnace will pass through the heater duct 16 and will heat the water in the pipes 26. This heated water will be displaced by the cold water flowing from the tank 27 through the pipe 28 and the heated water will flow upwardly through the hot water return pipe 29 back to the tank. This operation will continue until the water has been raised to the desired temperature whereupon the aquastat 32 will close the valve 11. The aquastat may control the motor 5, if desired.

It will be noted from Figure 1 that I mount a heat-limit control 34 at the top of the furnace and when the temperature in the furnace passes beyond a predetermined point, the control 34 will reduce the flow of gas to the burner by closing the gas valve 11. An electric conduit 35 is shown extending from the heat-limit control 34 to the gas valve.

From the foregoing description of the various parts of the device, the operation thereof may be readily understood.

When the room thermostat 9 closes, it will close an electric circuit which will cause the gas valve 11 to open and will also cause the thermostatically operated control motor 5 to open the damper 4. Heated air will be forced through the furnace by the blower 47 when the temperature in the furnace reaches a point to close the blower control switch 48 which in turn connects the blower with a source of current. This heated air will pass through the hot air duct 2 to the various

rooms, and a portion will be bypassed through the heater duct 16 because the damper 17 is partially open. The hot air flowing through the duct 16 will warm the water in the water heater 23 and this heated water will flow into the tank 27 in the manner already described. The heated air after being forced into the rooms will flow back to the furnace by means of the cold air return duct 3. The returning air will be warmer than the atmospheric air and therefore less heat will be necessary to maintain the rooms at a proper temperature. When the rooms do attain this necessary temperature, the thermostat 9 will cause the motor 5 to close the damper 4, whereupon all of the heated air will flow through the heater duct 16. This will continue until the water in the tank 27 is raised to the desired temperature. The valve 11 will remain open until the demands of the room thermostat 9 or the aquastat 32 are met. When the rooms are at the desired temperature and the water is also at the desired temperature, the valve 11 will close and shut off the gas to the burner.

During warm weather, the damper 4 will remain closed and the damper 17 will be held in wide-open position. The burner 14 will be turned on or off by the valve 11 solely according to the demand of the aquastat 32, except that if for any reason the temperature within the furnace should exceed the temperature at which the control 34 is set, this control will close the valve 11. A comparable condition will obtain during periods of demand by the room thermostat 9. The heated air will only flow through the heater duct 16 and will be returned to the furnace by the cold air duct 3. It is possible to mount a check damper 36 in the return duct 3 to prevent any possibility of the heated air passing through this duct and entering the house. If desired the damper 36 may be operatively connected to the damper 4 to be closed when the damper 4 is closed.

It will be seen that I provide two closed circuits for the heated air, one to the rooms and back to the furnace, and the other to the heat transferring means 23 and back to the furnace. The cost of operating the furnace is reduced to a minimum due to these two closed circuit features. Should the return duct 3 be dispensed with, the closed hot air circuits would also be eliminated and in this case the duct 16 could carry the heated air directly to the atmosphere. Such an arrangement would not be so economical as that contemplated by the closed hot air circuits. It is possible to have the return duct 3 eliminated and still have the duct 16 communicate with the lower end of the furnace so that the closed relation of the water heating duct 16 to the furnace be retained.

It should be noted that the room thermostat in opening the damper through the thermostatically operated control motor 5 actuates a contact in the control motor that electrically cuts out the aquastat so long as the room damper 4 is open. If this were not the case, the water upon being heated to the desired extent would cause the aquastat to shut off the burner and this would prevent the heat from entering the rooms. When the control motor closes the damper 4, the aquastat is again placed in electrical connection with the burner valve.

In the wiring diagram shown in Figure 3, the various units are shown diagrammatically and a wire 37 leads from a source of current to the furnace limit control switch 34 and from there a wire 38 leads to a relay 39 which may be mounted

in the damper motor housing 5 if desired. A wire 40 connects with the relay and with the room thermostat 9. A return wire 41 extends from the room thermostat to the motor (not shown), enclosed within the damper motor housing 5. A wire 42 leads from the motor to the burner valve 11 and a wire 43 extends from the burner valve back to the source of current.

When the room thermostat switch 9 is closed, the current will flow to actuate the damper motor 5 and to open the burner valve 11. The current is controlled by the room thermostat 9 and the furnace limit control switch 34. The current energizes the relay 39 and opens a switch 44 which will break the circuit through the aquastat 32. When the room thermostat switch 9 is opened, the switch 44 will be closed because the relay 39 becomes de-energized and then when the aquastat switch 32 closes, a current will flow through the wire 37, the furnace limit control switch 34, wire 38, wire 35, aquastat 32, wire 44a, switch 44, wire 46 to the wire 42, burner valve 11, wire 43, and back to the source of current. The water in the tank 27, when heated to the proper temperature, will open the aquastat switch 32. The furnace limit control switch 34 is a safety precaution to prevent the temperature in the furnace from rising to too high a degree. In Fig. 3, I have indicated the conduits 10, 12, 33 and 35 by dot dash lines. The blower 47 and switch 48 are on a separate circuit which connects with the source of current.

The invention is not to be restricted to a closed hot air system. The return cold air duct is to be regarded as a means for supplying cold air to the furnace, or generally, air having a temperature less than that of the air delivered by the furnace.

In the modified form of the invention shown in Figures 4 and 5 a portion of the cold air return conduit 50 (corresponding to the conduit 3) forms a part of the casing 51 that houses the hot air furnace 52. A partition 53 divides the casing 51 into two compartments 54 and 55. A blower 56 is placed in the compartment 55 and draws air from the cold air conduit 50 and forces it into the furnace compartment 54. From there the air is usually forced into the hot air conduit 57 that leads to the rooms or space to be heated. A damper 58 is designed to close the hot air conduit 57 and a damper 59 is designed to close the cold air return conduit 50. These two dampers have arms 58a and 59a that are operatively connected together by a link 60 so that both dampers will be opened and closed simultaneously. A damper control motor 61, similar to the control motor 5, is connected to the damper arm 58a by a link 62. A room thermostat 63 is electrically connected to the damper control motor 61 in a manner hereinafter described and when the temperature in the room drops to a predetermined point, the room thermostat will close an electric circuit through the damper control motor for causing both dampers to swing into open position.

I show an oil burner 64 in Figure 4 and the closing of the room thermostat 63 will cause the oil furnace to function. Hot air will be given off by the furnace 52 and this air will flow through the conduit 57 to the rooms and cold air will return by the conduit 50 back to the compartment 55 and thence to the furnace compartment 54, thus completing a closed hot air circuit. A blower control switch 65 is electrically connected to the blower 56 in a manner hereinafter described, so that when the temperature of the hot air issuing from the furnace reaches about 175° F.,

the blower 56 will be automatically started and will force the heated air to the rooms and will draw the cold air from the rooms. In this way no cold air is blown into the rooms.

5 A limit control switch 66 is electrically connected to the burner 64 for opening the circuit to the burner and stopping it from functioning when the temperature of the furnace reaches 250° F. The switch 66 will close when the temperature drops below 175° F., and in this way the limit control switch protects the furnace.

10 The hot water tank 67 is similar to the hot water tank 27 and is connected to a hot water heater 68 (similar to the hot water heater 23) by pipes 69 and 70. The heater 68 is placed in the hot air compartment 54 at a point adjacent to an opening 71 in the partition 53. A by-pass damper 72 partially closes the opening 71 when the dampers 58 and 59 are fully open. The 15 damper 72 is fully open when the dampers 58 and 59 are closed. A link 73 operatively connects an arm 72a of the damper 72 with an arm 58b of the damper 58 so that all three dampers will be actuated simultaneously by the damper 20 control motor 61. A hood 74 may be placed over the heater 68 for directing the heated air from the compartment 54 into the compartment 50 when the dampers 58 and 59 are closed and the damper 72 opened.

25 30 An aquastat 75 is placed in the water tank 67 and is electrically connected by a circuit herein-after described with the oil burner 64 for causing the latter to function when the aquastat switch closes even though the room thermostat 63 re-35 mains open.

35 The wiring circuit for the device shown in Figure 4 is shown in Figure 5. A wire 76 leads from a source of current and connects with the room thermostat 63. A wire 77 leads from the thermo-40 stat to the damper control motor 61. A wire 78 leads from the motor to a relay 79 and from thence to the limit control switch 66. A wire 80 leads from the limit control switch 66 to a stack switch 81. Figure 4 shows the stack switch placed 45 in the smoke pipe 82 that leads from the furnace 52. Any type of switch 81 may be used and I have shown a bi-metal member 83 that will open the switch 81 when the heat in the pipe exceeds a predetermined point. A wire 84 leads from the 50 switch 81 to the oil burner 64 and a wire 85 leads from the burner back to the source of current.

55 When the room thermostat 63 closes, current will flow through the various wires and units just mentioned and the burner 64 will be ignited. The damper control motor 61 will open the dampers 58 and 59 and swing the by-pass damper 72 to a point where it will remain only partially open. As soon as the temperature of the furnace reaches 175° F., the switch 65 will close the circuit to the 60 blower 56 through the wires 86, 87, and 88 and this will cause the blower to draw air in from the conduit 50 and to force air through the compartment 54 and into the conduit 57. A closed hot air circuit is now established between the furnace 65 and rooms. As already stated, the blower is automatically turned on and off by the switch 65 which in turn is controlled by the temperature in the compartment 54.

70 It will be noted that during the time the room thermostat 63 is closed, the aquastat 75 will be disconnected from the burner 64 by the opening of a switch 89. The switch is opened by the energizing of the relay 79 and the relay will remain energized so long as the room thermostat 63 is closed. Figure 4 shows that a portion of the hot

air issuing from the compartment 54 will pass into the hood 74 and through the opening 71 which is partially closed by the damper 72. The water heater 68 is heated to a certain extent so that the water temperature will be raised in the water tank 67.

When the room thermostat 63 opens, the relay 19 will be de-energized and the switch 89 will close. Now if the aquastat 75 closes due to the water in the tank 67 calling for heat, the wire 90, connected to the wire 86, will place the switch 75 in electrical connection with the wire 76 and a wire 91 leading from the aquastat 75 to the closed switch 89 will connect the aquastat with the wire 78, thus completing a circuit to the oil burner 64. The opening of the switch 63 causes the dampers 58 and 59 to be closed by the damper control motor 61 and causes the by-pass damper 72 to be fully opened. All of the heat will now pass through the hood 74 and the opening 71 and this will heat the water in the water heater 68 so that the temperature of the water in the tank 67 will be quickly raised. The blower 56 will be started automatically when the switch 65 is closed which means that the heat in the compartment 54 has reached a temperature of 175° F. This second closed hot air circuit from the compartment 54 into the hood 74, past the water heater 68, through the opening 71, into the compartment 55, and from the blower 56 back to the compartment 54 will continue until the aquastat 75 is satisfied. The heat builds up rapidly because there is little heat loss. The limit control switch 66 stops the burner before an excessive temperature is reached while the blower remains in operation so long as there is sufficient heat in the compartment 54. The burner starts again when the temperature drops to 175° F., by the closing of the switch 66, provided that either the thermostat 63 or the aquastat 75 is demanding heat.

It is possible to dispense with the hood 74 and to cause a portion of the heated air flowing through the conduit 57 to heat the water heater 68. I find better results however, by using the hood and keeping the by-pass damper partially open when the dampers 58 and 59 are fully open.

In Figure 6 I show a slightly modified form of the device from that illustrated in Figure 4. In the modified form, the hood 74 is dispensed with and the damper or valve 72b is so connected to the arm 58b by the link 73 and the arm 72a as to be entirely closed when the valve or damper 58 is fully open. The parts of the device shown in Figure 6 which are similar to the parts shown in Figure 4 have been given corresponding reference numerals.

In the operation of this form of the invention an opening of the dampers or valves 58 and 59 and the entire closing of the damper or valve 72b will cause the heated air to flow from the hot air furnace 52 up through the conduit 57 to the space to be heated and the cold air to be returned by the conduit 58. A portion of the heated air flowing from the furnace 52 and entering the conduit 57 will contact the water heater 68 and will heat the water therein so that this heated water will be conducted to the water tank 67. In this way the furnace will heat both the space to be heated and the water in the tank 67 when the room thermostat 63 is closed. Only a portion of the heated air flowing into the conduit 57 will contact with the water heater 68 due to the position the water heater occupies in the compartment 54.

When the room thermostat 63 is satisfied, the dampers or valves 58 and 59 will close and the damper or valve 72b will be fully opened. If now the water temperature drops below a predetermined point in the tank 67, the aquastat 75 will close an electric circuit to the burner 64 and cause the furnace 52 to deliver heated air into the compartment 54. This heated air will flow past the water heater 68 and then pass through the opening 71 into the compartment 51. The blower 56 will function when the temperature of the heated air reaches a certain point and the closed hot air circuit for the hot water heater 68 will continue functioning until the aquastat 75 is satisfied.

Still another modified form of the invention is shown in Figure 7. Here the furnace 100 is placed in a casing compartment 101 which is similar to the compartment 54. A damper 102 or valve is placed in a hot air conduit 103 leading from the compartment. A return cold air conduit 104 conveys the air from the space to be heated back to a compartment 105. The compartment 105 is in the same casing that houses the compartment 101 and is separated therefrom by a partition 106. A blower 107 is placed in the compartment 105 and draws the air from the return duct 104 and delivers it through a passage 108 into the lower portion of the compartment 101. The returning air passes through air filters shown at 109 in the compartment 105.

A cold air damper 110 is placed in the return conduit 104 and is operatively connected to the damper 102 so that an opening of the damper 102 will cause the cold air damper 110 to swing downwardly and open the cold air return duct 104. The damper 102 is pivoted at 111 and has an arm 112 that is connected by a link 113 to an arm 114 which in turn, swings the cold air damper 110 about its pivot 115. A damper control motor 116 similar to the motor 61, has its arm 117 connected to the arm 112 by means of a link 118. A room thermostat 119 is in electrical connection with the motor 116 so that when the temperature in the space to be heated drops below a predetermined point, the thermostat will close an electric circuit to cause the burner 120 to heat the air in the furnace 100. The thermostat will also cause the damper control motor 116 to swing the dampers 102 and 110 into positions for opening the conduits 103 and 104.

I provide an opening 121 in the partition 106, this opening being closed by the cold air damper 110 when the damper is swung into a position to open the return conduit 104. In this way the damper 110 performs two functions; in one position it closes the conduit 104 and uncovers the opening 121 whereas in the other position it closes the opening 121 and opens the conduit 104. I place a hot water heater 122 in the compartment 101 and adjacent to the opening 121. This hot water heater is connected by water pipes 123 and 124 to a hot water storage tank 125 so that a heating of the water in the hot water heater 122 will heat the water in the tank 125. The tank 125 has a cold water inlet 126 and a hot water outlet 127. An aquastat 128 is placed in the hot water tank 125 and will be electrically connected to the burner 120 when the water in the tank 125 drops below a predetermined temperature and when the room thermostat 119 is satisfied.

The operation of this form of the invention is somewhat similar to the form shown in Figure 6 in that when the thermostat 119 closes, the

damper motor 116 will cause the dampers 102 and 110 to open the conduits 103 and 104. The closing of the thermostat also starts the burner 120 and hot air will flow from the furnace through the conduit 103 to the rooms or space to be heated and cold air will return through the conduit 104. The damper 110 performs the function of the two dampers 59 and 72b in the form of the device shown in Figure 6 because when the damper 110 opens the conduit 104, it will close the opening 121. A portion of the hot air flowing into the conduit 103 will pass the hot water heater 122 and cause the water in the heater to be raised in temperature.

When the room thermostat 119 is satisfied, the dampers 102 and 110 will close the conduits 103 and 104. The damper 110 in closing the conduit 104 will uncover the opening 121 and this will make a direct passage for the hot air from the compartment 101 into the compartment 105. If now the temperature of the water in the tank 125 drops below a predetermined point, the aquastat 128 will close an electric circuit to the burner 120 and the hot air from the furnace 100 will flow past the water heater 122 and through the opening 121 into the compartment 105. The blower 107 will aid this flow of air in the closed hot air circuit and the flow will continue until the aquastat 128 is satisfied.

The wiring diagram for both Figures 6 and 7 can be the same as that shown in Figure 5 where a line voltage control circuit is shown throughout. Such wiring as is shown in Figure 7 follows the scheme disclosed in Figure 8. In Figure 8, I show a modern automatic control for the device of Figure 7, in which the actual control circuits operate on twenty-four volts furnished by a small transformer provided in the main stack relay. The line voltage is used for the damper motor, the burner and the blower and connections are made by relays placed in the stack relay. Such controls are standard so I have indicated the wiring in Figure 8, somewhat diagrammatically. A brief description will suffice. The same wiring can be used with the other devices in Figures 1, 4 and 6.

The main voltage lines 128a and 129 connect with the damper motor 116. The stack relay shown at 81a is connected by wires 130 and 131 to the lines 128a and 129 and is connected to the burner 120 by wires 132 and 133 carrying the line voltage. The blower motor 107 is connected to the wires 130 and 131 by wires 134 and 135, the wire 134 having the blower control 65 in series therewith.

The low voltage control circuit comprises the three wires 136 connecting the room thermostat 119 with the damper motor 116. The thermostat 119 may be of the two contact type where the closing of the thermostat when the temperature drops below a predetermined point will cause the damper motor to make a one-half revolution to move the arm 117 through 180° to open the dampers, and when the desired air temperature is reached, the closing of a second switch in the thermostat will cause the damper motor to make the other half revolution to swing the arm 117a through another 180° and close the dampers.

Two low voltage wires 137 and 138 lead from the stack relay 81a to the furnace limit control 66 and have the aquastat 128 in series therewith. Two shunt or short circuit wires 139 and 140 lead from opposite sides of the aquastat to a shunt switch (not shown) in the damper motor 116. When the thermostat 119 is closed for heating

the house, the shunt switch is closed and will short circuit the wire 137 leading to the aquastat so as to make the action of the aquastat of no avail.

5 The circuit causes the parts to operate as already explained and no further description need be given except to say that when the damper motor 116 opens the dampers 102 and 110, the auxiliary or shunt switch (not shown), closes to 10 by-pass the aquastat, leaving the limit control switch 66 to control the burner through the stack relay (not shown). When the dampers are closed by the damper motor, the auxiliary switch opens, cutting the aquastat back into the circuit. The auxiliary switch could take the place of the relay 79.

I claim:

1. The combination with a hot air furnace having a hot air duct leading therefrom to one or more rooms and a cold air return duct leading from the one or more rooms back to the furnace, a damper for the hot air duct, thermostatically controlled means responsive to the room temperature for opening and closing the damper, of a heater duct communicating with the hot air duct between the damper and the furnace and also communicating with the return duct, a water heater placed in the heater duct, a hot water tank, pipe connections between the tank and heater for causing water heated in the heater to be transferred to the tank, a damper mounted in the heater duct and operatively connected to the first-named damper so that it will be partially opened when the first damper is fully opened 20 and it will be fully opened when the first damper is closed, a burner for the furnace, a valve-controlled fuel supply for the burner, an aquastat for the hot water tank, separate means connecting the aquastat and thermostat to the fuel valve 25 for controlling the flow of fuel to the burner, and means conditioned by the satisfaction of the thermostat for making the aquastat connection effective when the aquastat is unsatisfied.

2. The combination with a hot air furnace having a burner, a fuel pipe for the burner, an electrically controlled valve for regulating the fuel passing to the burner, a hot air duct leading from the furnace, a cold air return duct communicating with the furnace, a heater duct communicating 45 with the hot air duct and return duct, a damper for the hot air duct, a second damper for the heater duct, means connecting the two dampers together for maintaining the second damper partially open when the first damper is fully opened 50 and for fully opening the second damper when the first damper is closed, a thermostatically controlled motor operatively connected to the first damper, a room thermostat for controlling the motor, a water heater placed in the heater conduit, a hot water tank connected to the heater for receiving hot water from the heater, an aquastat associated with the tank, a heat limit thermostat in the furnace, separate means connecting the aquastat, room and furnace thermostats 55 to the fuel valve for controlling the flow of fuel to the burner, and means conditioned by the satisfaction of the thermostat for making the aquastat connection effective when the aquastat is unsatisfied.

3. The combination with a closed hot air circuit for a house including a hot air furnace, a hot air conduit for conveying hot air from the furnace to the rooms and a cold air conduit for conveying cold air from the rooms back to the furnace, of a 70 second closed hot air circuit including the fur-

11

nace, the hot air conduit, the cold air conduit, and a heater conduit communicating with both the hot and cold air conduits, a hot water heater placed in the heater conduit, a water tank communicating with the hot water heater for receiving hot water therefrom, a damper for the hot air conduit, a second damper for the heater conduit, and means interconnecting the dampers for swinging the heater damper toward partially closed position when the hot air conduit damper is opened, and for swinging the heater damper toward open position as the hot air conduit damper is swung toward closed position.

4. In a hot air heating and domestic hot water supply system; the combination with a hot air heating circuit including a heater, a first casing surrounding said heater, a space to be heated, supply and return conduits connecting said first casing to said space and providing for the circulation of heated air from said casing to the space and back to the casing; of a domestic hot water heating circuit, including a second casing, water heating means within said second casing, conduit means connecting said second casing to said supply and return conduits, motor controlled damper means at the junction of the said supply conduit and said conduit means, thermostatic means responsive to the temperature of the air in said space regulating said motor controlled damper means to provide for the circulation of heated air to said space, or to said second casing.

5. The combination with a hot air furnace having a cold air inlet leading from the rooms to the furnace, a hot air duct leading from the furnace to the rooms, a heater duct communicating with the hot air duct and with the cold air inlet, a hot water heater placed in the heater duct, a hot water tank, connections between the heater and the tank for transferring heated water from the heater to the tank, a burner for the furnace, a thermostat for the rooms and an aquastat for the tank separate means controllably connecting the thermostat and aquastat to the burner, means conditioned by the satisfaction of the thermostat for making the aquastat connection effective when the aquastat is unsatisfied, and means also controlled by the thermostat for controlling the hot air flow into the hot air duct and the heater duct for raising the room and water temperatures.

6. The combination with a closed hot air circuit for a house including a hot air furnace, means for conveying hot air from the furnace to the rooms and from the rooms back to the furnace, a second closed hot air circuit including the furnace as a part of the circuit, a hot water heater placed in the second circuit, a water tank connected with the heater for receiving hot water from the heater, a burner for the furnace, a thermostat in the rooms and automatically lighting the burner when the room temperature drops below a predetermined point, an aquastat for the water tank and automatically lighting the same burner when the water temperature drops below a predetermined point if the thermostat is satisfied, dampers for controlling the flow of hot air through both closed hot air circuits, and a thermostatically operated control motor connected with the room thermostat for causing the dampers to direct the greater portion of hot air to the rooms when the room thermostat lights the burner.

7. In a hot air heating and domestic hot water supply system, the combination of a hot air fur-

12

nace, a burner for the furnace, a first hot air circuit having supply and return conduits connecting the furnace to the space to be heated, a second hot air circuit communicating with the upper and lower portions of and including the furnace as a part of the circuit, a water heating system arranged in heat exchange relation to the hot air in the second circuit, separate valve means for respectively controlling hot air flow in the circuits, a thermostat responsive to the temperature of the space and operably connected to the valve means for controlling their positions, an aquastat responsive to the temperature of the water in the water heating system, and means including electrical connections between the thermostat and burner and the aquastat and burner whereby the thermostat exercises primary control on the burner and the aquastat controls the burner when the thermostat is open.

8. A hot air heating and domestic hot water supply system comprising a closed hot air heating circuit including a heater, a casing surrounding said heater, a space to be heated, supply and return conduits connecting said casing to said space and providing a hot air heating circuit for the circulation of heated air from said casing to the space and back to the casing; of a domestic hot water heating circuit including said heater, water heating means disposed within said domestic hot water heating circuit and connected to a hot water tank; thermostatically controlled means sensitive to the air temperature in said space for turning on the heater, said means including a damper for directing the heated air into the first hot air heating circuit when the air temperature in said space drops below a predetermined point and for causing the damper to close the first hot air heating circuit when the thermostat is satisfied; an aquastat sensitive to the water temperature in said tank for turning on the heater when the damper is closed; a second damper operatively connected to the first damper and being opened when the first damper is closed for directing the heated air into the domestic hot water heating circuit when the water temperature drops below a predetermined point, said second damper being held partially open when the first damper is fully open for causing some heated air to flow into the domestic hot water heating circuit when the heated air is flowing through the closed hot air heating circuit.

9. The combination with a casing divided into two compartments by a partition, a hot air furnace placed in one compartment, a conduit leading from the furnace compartment to the space to be heated and a return conduit leading from the space to the other compartment, a damper mounted in each conduit, thermostatically controlled means for simultaneously opening both dampers when the air temperature in said space drops below a predetermined point, said partition having a by-pass opening, a by-pass damper adapted to close the opening and being operatively connected to said first-named dampers so that a closing of the first-named dampers will open the by-pass damper and vice versa, a water heater placed adjacent to the by-pass opening so that hot air flowing through the opening will heat the water in the heater, and a water tank connected to the water heater for receiving hot water from the heater.

10. In combination, a casing divided into two compartments by a partition, a furnace placed in one compartment and a blower in the other for forcing air from the latter compartment into

13

the furnace compartment, a conduit leading from the furnace compartment to the space to be heated, and a second conduit leading from the space back to the blower compartment, a damper for the first-named conduit, a thermostat in said space for opening the damper when the temperature in the space drops below a predetermined point, said partition having a by-pass opening for permitting heated air to flow from the furnace compartment into the blower compartment when the damper is closed, a by-pass damper operatively connected to the first-named damper and being opened when the first damper is closed, a water heater placed near the by-pass opening and in the furnace compartment, a hood for directing hot air from the furnace compartment past the heater and through the by-pass opening when the first damper is closed, a hot water storage tank communicating with the water heater an aquastat for the tank, a burner for the furnace, separate means connecting the aquastat and thermostat to the burner for controlling the flow of fuel to the burner, and means conditioned by the satisfaction of the thermostat for making the aquastat connection effective when the aquastat is unsatisfied.

11. In a hot air heating and domestic hot water supply system, the combination of a hot air furnace, a burner for the furnace, a first hot air circuit having supply and return conduits connecting the furnace to the space to be heated, a second hot air circuit communicating with upper and lower portions of and including the furnace as a part of the circuit, a water heating system arranged in heat exchange relation to the hot air in the second circuit, separate valve means for respectively controlling hot air flow in the circuits, a thermostat responsive to the temperature of the space and including means operably connected to the valve means for controlling their positions, an aquastat responsive to the temperature of the water in the water heating system, and means including electrical connections between the thermostat and burner and the aquastat and burner whereby the thermostat exercises primary control on the burner and the aquastat controls the burner when the thermostat is open, the separate valve means being connected for simultaneous movement and the first circuit valve means being closed when the second circuit valve means is open.

12. In a hot air heating and domestic hot water supply system, the combination of a hot air furnace, a burner for the furnace, a first hot air circuit having supply and return conduits connecting the furnace to the space to be heated, a second hot air circuit communicating with upper and lower portions of and including the furnace as a part of the circuit, a water heating system arranged in heat exchange relation to the hot air in the second circuit, separate valves in the supply and return conduits and in the second circuit for controlling hot air flow therethrough, a thermostat responsive to the temperature of the space and including means operably connected to all of the valves for controlling their positions, an aquastat responsive to the temperature of the water in the water heating system, and means including electrical connections between the thermostat and burner and the aquastat and burner whereby the thermostat exercises primary control on the burner and the aquastat controls the burner when the thermostat is open.

13. In a hot air heating and domestic hot water supply system, the combination of a hot air fur-

14

nace, a burner for the furnace, a first hot air circuit having supply and return conduits connecting the furnace to the space to be heated, a second hot air circuit communicating with upper and lower portions of and including the furnace as a part of the circuit, a water heating system arranged in heat exchange relation to the hot air in the second circuit, separate valves in the supply and return conduits and in the second circuit for controlling hot air flow therethrough, a thermostat responsive to the temperature of the space and including means operably connected to all of the valves for controlling their positions, an aquastat responsive to the temperature of the water in the water heating system, and means including electrical connections between the thermostat and burner and the aquastat and burner whereby the thermostat exercises primary control on the burner and the aquastat controls the burner when the thermostat is open, the separate valves being connected for simultaneous movement and the first circuit valves being closed when the second circuit valve is open.

14. In a hot air heating and domestic hot water supply system, the combination of a hot air furnace, a hot air supply conduit leading from the furnace to the space to be heated, a conduit for conveying cold air to the furnace, a local hot air circuit communicating with upper and lower portions of and including the furnace as a part of the circuit, separate valve means in the supply conduit and local circuit at the upper connection with the furnace, respectively, for controlling hot air flow therethrough, and water heating means positioned anterior to the local circuit valve means and in constant heat exchanging relation with the air in the furnace.

15. In a hot air heating and domestic hot water supply system, the combination of a hot air furnace, a hot air supply conduit leading from the furnace to the space to be heated, a conduit for conveying cold air to the furnace, a local hot air circuit comprising the furnace and cold air conduit as parts of the circuit and a connection between the upper portion of the furnace and the cold air conduit, first valve means for controlling hot air flow through the supply conduit, second valve means located in the connection for controlling hot air flow therethrough, and water heating means positioned anterior to the second valve means and in constant heat exchanging relation with the air in the furnace.

16. In a hot air heating and domestic hot water supply system, the combination of a hot air furnace, a hot air supply conduit leading from the furnace to the space to be heated, a conduit for conveying cold air to the furnace, a local hot air circuit communicating with upper and lower portions of and including the furnace as a part of the circuit, separate valve means in the supply conduit and local circuit at the upper connection with the furnace, respectively, for controlling hot air flow therethrough, a thermostat in the space, means responsive to the thermostat for determining the positions of the valve means, and water heating means positioned anterior to the local circuit valve means and in constant heat exchanging relation with the air in the furnace.

17. In a hot air heating and domestic hot water supply system, the combination of a hot air furnace, a hot air supply conduit leading from the furnace to the space to be heated, a conduit for conveying cold air to the furnace, a local hot air circuit communicating with upper and lower portions of and including the furnace as a part

of the circuit, first valve means in the supply conduit and second valve means in the local circuit at the upper connection with the furnace for controlling hot air flow, the valve means being connected for simultaneous movement, and water heating means positioned anterior to the second valve means and in constant heat exchanging relation with the air in the furnace.

18. In a hot air heating and domestic hot water supply system, the combination of a hot air furnace, a hot air supply conduit leading from the furnace to the space to be heated, a conduit for conveying cold air to the furnace, a local hot air circuit communicating with upper and lower portions of and including the furnace as a part of the circuit, first valve means in the supply conduit and second valve means in the local circuit at the upper connection with the furnace for controlling hot air flow, the valve means being connected for simultaneous movement, a thermostat in the space, means responsive to the thermostat for determining the positions of the valve means, and water heating means positioned anterior to the second valve means and in constant heat exchanging relation with the air in the furnace.

19. In a hot air heating and domestic water supply system, the combination of a hot air furnace, a burner for the furnace, a conduit connecting the furnace to the space to be heated, a second conduit for receiving heated air from the furnace, a water heating system arranged in heat exchange relation to the hot air in the second conduit, separate valve means for respectively controlling hot air flow in the conduits, a thermostat responsive to the temperature of the space and including means operably connected to the valve means for controlling their positions, an aquastat responsive to the temperature of the water in the water heating system, and means including electrical connections between the thermostat and burner and the aquastat and burner whereby the thermostat exercises primary control on the burner and the aquastat controls the burner when the thermostat is open.

20. In a hot air heating and domestic water supply system, the combination of a hot air furnace, a burner for the furnace, a first hot air circuit having supply and return conduits connecting the furnace to the space to be heated, a second hot air circuit communicating with upper and lower portions of and including the furnace as a part of the circuit, a water heating system arranged in heat exchange relation to the hot air in the second circuit and also arranged in heat exchange relation to a portion of the hot air in the first hot air circuit, separate valve means for respectively controlling hot air flow in the circuits, a thermostat responsive to the temperature of the space and including means operably connected to the valve means for controlling their positions, an aquastat responsive

to the temperature of the water in the water heating system, and means including electrical connections between the thermostat and burner and the aquastat and burner whereby the thermostat exercises primary control on the burner and valve means for causing hot air to flow through the first hot air circuit and shutting off any hot air flow through the second hot air circuit when the thermostat needs to be satisfied, the thermostat when satisfied causing the valve means to close the first hot air circuit and open the second hot air circuit, and the aquastat controls the burner when the thermostat is open for causing hot air to flow through the second hot air circuit.

21. In a hot air heating and domestic hot water supply system, the combination of a hot air furnace, a burner for the furnace, a first hot air circuit having supply and return conduits connecting the furnace to the space to be heated, a second hot air circuit communicating with the upper portion of the furnace and with the return conduit as a part of the circuit, a water heating system arranged in heat exchange relation to the hot air in the second circuit and also arranged in heat exchange relation to a portion of the hot air in the first hot air circuit, separate valves in the supply and return conduits and connected together so that the conduits are either opened or closed simultaneously, the valve for the return conduit closing the second air circuit when opening the return conduit, a thermostat responsive to the temperature of the space and including means operably connected to both valves for controlling their positions, an aquastat responsive to the temperature of the water in the water heating system, and means including electrical connections between the thermostat and burner and the aquastat and burner whereby the thermostat exercises primary control on the burner for lighting the burner and causing the valves to open the conduits for the first hot air circuit and close the second hot air circuit, the valves closing the conduits and opening the second hot air circuit when the thermostat is satisfied, and the aquastat when needed to be satisfied controls the burner when the thermostat is open for causing hot air to flow through the second hot air circuit.
